INVENTOR

PATRICK A. FLYNN

By E. B. Burkenbueel

His ATTORNEY

UNITED STATES PATENT OFFICE.

PATRICK A. FLYNN, OF PORTLAND, OREGON.

NUT LOCK.

Application filed July 15, 1922. Serial No. 575,188.

To all whom it may concern:

Be it hereby known that I, PATRICK A. FLYNN, a citizen of the United States, and a resident of Portland, in the county of Multnomah and State of Oregon, have invented a new and useful Nut Lock, of which the following is a specification.

This invention relates more particularly to means for locking nuts and bolts against turning.

The objects of my invention are to provide an exceedingly simple and efficient nut lock which will be low in cost and efficient in operation.

15 A further object is to so construct same that the unlocking operation can be easily accomplished without injury to the nut or threads on the bolt.

I attain these results in the manner set forth in the following specification and illustrated in the accompanying drawing, in which:

Figure 1 is a front elevation of a nut equipped with my lock. Figure 2 is a side elevation of Figure 1 and Figure 3 a plan of same. Figure 4 is an enlarged elevation of the locking pin of which Fig. 5 is a plan. Figure 6 is an elevation of a second form of my device. Figure 7 is an elevation of 30 a third form of my device of which Figure 8 is a plan. Figure 9 is an elevation of a fourth form of the device of which Figure 10 is a plan.

Similar numbers of reference refer to the same or similar parts throughout the several views.

Referring in detail to the drawing, I have constructed my device in the form of a lock for the nut 11 whose sides 12 have the slot 13 formed therein. Into the hole 14 is driven a pointed pin 15 one side of whose upper end 16 is cut away and having the slot 17 formed therein. The portion 18 is bent outwardly to form a spring latch whose end 19 will engage the under side 20 of the slot 13 when the point 21 is driven into the metal 22 against which the nut 11 bears.

In Fig. 6 I have shown a pin 15^A similar to pin 15 except that the slot 17 is omitted and the end 16 is curved outwardly. A notch 23 may be provided in the side of the

pin 15^A to assist in releasing the pin when it is desired to turn the nut or bolt.

In Figure 7 I have illustrated a pin 15^B 55 from whose middle the split portion 24 projects.

In Figure 9 I have illustrated the pin 15^C whose entire length is curved and its convex side 25 is cut away along the line 26 to form 60 a spring for holding the shoulder 27 under the edge 20. It will be understood that sufficient play must be provided between the hole 14 and the pin 15^C to permit easy movement. A head 28 is provided for the pin 65 15^C to assist in withdrawing the pin instead of using the notch 23, as previously suggested.

It will be understood that the same lock can be used at the head end of a bolt where 70 it is desired to keep the bolt from turning.

Attention is drawn to my United States Patent No. 1,363,504 December 28, 1920 for a lock nut, over which this invention is an improvement.

I am aware that many forms of nut locks have been invented in the past, I therefore intend to cover only such forms and modifications of this device as fall fairly within the appended claims.

What I claim as new is:

1. A nut lock consisting of a nut having a slot cut in its side across one of its corners and having a hole parallel to its tapped opening passing through said slot, in combination with a pointed spring pin adapted to be driven through said hole, said pin having a shoulder formed thereon adapted to be sprung under the upper edge of said slot when the point of said pin projects 90 from said nut.

2. A nut lock consisting of a nut having a hole drilled through one corner parallel to its axis and having a slot cut into said hole from the side, in combination with a 95 pointed pin having a spring latch formed thereon by splitting said pin and shortening one of its sides and bending same outwardly in a manner that said shortened side can lock under the upper side of said slot, and having a notch cut in the shortened side of said pin to facilitate its removal.

PATRICK A. FLYNN.
